PORTABLE DRAFTING MACHINE

George C. Luebckeman, Cincinnati, Ohio

Application May 3, 1952, Serial No. 285,879

9 Claims. (Cl. 33—79)

1

This invention relates to drafting machines and has for an object the provision of a primarily portable device which can be conveniently carried in the coat pocket or in the briefcase and which is primarily adapted for comfortable and accurate use and ambulatory adjustment with one hand without necessitating the employment of fastening means on the drawing surface.

Another object of the invention is to provide a simple, reliable and relatively inexpensive device for the stated purposes which device affords to the user an exceptionally easy and rapid adjustment to the requirements in making or checking a drawing of any size.

A further object of the invention is to provide a machine of this character which is provided with means adapting it to use in environments other than on a drawing board without loss of its advantages of easy and extremely flexible ambulatory and swinging adjustments.

These and other important objects, hereinafter made apparent, are attained by the means described herein and exemplified in the accompanying drawings, in which:

Fig. 1 is a perspective view of a pocket drafting machine embodying the invention operatively held by the user's hand.

Fig. 2 is a top plan view of the device, partly broken away.

Fig. 3 is a cross sectional view taken on line 3—3 of Fig. 2.

Fig. 4 is a cross sectional view taken on line 4—4 of Fig. 2.

Fig. 5 is a cross sectional view taken on line 5—5 of Fig. 2.

Fig. 6 is a cross sectional view taken on line 6—6 of Fig. 2.

Fig. 7 is a cross sectional view showing a means for securing the machine to a small portable drawing board.

It is known in the art to employ a jointed parallel arm assembly having at its opposite ends a drafting square and a base or another drafting instrument, the base forming portion being either permanently or temporarily secured to the drawing board in use.

It is the particular object of the invention to provide a drafting machine that is primarily adapted for convenient and accurate use without the necessity of employing any securing means, but is nevertheless capable of exceptionally easy adjustment which affords the operator a reliable, comfortable and very flexible control of the machine in its desired relation to any portion of a drawing surface. The manipulation is under practically all circumstances controlled by one hand of the user while the user's other hand is free to execute the drawing or checking of lines with a pencil or comparable instrument.

2

In its preferred form the drafting machine employs as a base or normally stationary member a protractor 8, which may be of transparent plastic material, having a true diameter line 9 thereon which is parallel to a straight edge 10 of the protractor. At the true radial center of the protractor 8 there is provided a finger piece 11 with a reduced cylindrical stem 12 which may turn freely and reciprocate slightly in a bore 13 that is centered exactly at the true radial center of the protractor. Counterbores 14 and 15 are provided in the top and bottom faces of the protractor to selectively receive the upper and lower disc-like enlargements 16 and 17 respectively on the ends of stem 12 which spaces said enlargements from each other at a distance sufficient to allow the enlargement 17 to shift into or slightly out of counterbore 15 and selectively engage the antiskid surface 18 of enlargement 17 on a drawing surface when digital pressure is applied on top of piece 11 and to thus permit the protractor 8 to be adjusted about its true radial center. The finger piece 11 also has an axial bore 19 to admit a pencil point or a push pin for marking or for temporarily holding the true radial center on the drawing if desired when the drawing and the device are left idle. The base or protractor 8 also has bores 20—20 adjacent opposite ends of the true diameter line 9 for marking or securing purposes if desired. A suitable clamp such as 21 may be employed having a slender lug 22 for entry into one of the bores 19 or 20 for temporarily fixing the machine on a small drawing board 23 if such a combination is wanted.

The semicircular margin of protractor 8 is suitably graduated as at 24 through one hundred eighty degrees on one side of diameter line 9 and is provided in known manner with re-

versely readable indicia 25 and 26.

The important feature of the present drafting machine of the invention is its combination of simple means which afford an improved maneuverability of the machine in a stepwise ambulatory fashion over successive areas of a drawing surface and the relative adjustment of its members on opposite ends of the jointed arm assembly 27 to carry on the drafting or checking operations without the use of fastening means. An L-square indicated generally at 28 or any other drawing implement is pivotally connected at one end of the arm assembly 27, which assembly is pivoted at its opposite end to the base or protractor member 8.

As shown in the drawings, assembly 27 comprises an annular joint member 29 which has the ends of a pair of parallel links 30—31 pivoted on its top at diametrically opposite sides thereof by means of rivets at 32 and 33. The links 30

and 31 have their remaining ends pivoted on top of the L-square on rivets 34 and 35 that are located on the longitudinal center of the drawing scale 36 which may be an integral or a removable part of said L-square 28. An upstanding finger knob 37 is mounted between the pivots 34 and 35 and relatively closer to the pivot 34 so that the stem of the knob 37 serves as a stop for arm 30 to limit the pivotal movement of L-square 28 in one direction about its pivots 34 and 35. A stop pin 38 (or in lieu thereof another knob similar to 37) located relatively close to the pivot 35, limits pivotal movement of arm 31 in the opposite direction. The links 39 and 40 cannot approach each other closely enough to impair the accuracy of their parallel relation.

The remaining links 39 and 40 respectively have ends pivoted on rivets 41 and 42 to the lower face of joint member 29 at diametrically opposite sides thereof. I preferably dimple the member 29 to provide shallow dished places in its top face to receive the heads of the pivot forming rivets 41 and 42 in substantially countersunk relation with the top face of member 29. The member 29 has the heads of rivets 32 and 33 substantially countersunk in shallow dished places in the bottom face of said member 29. This arrangement affords a sturdy mounting and interference free operation of the pivoted links on the annular joint member 29.

The remaining ends of links 39 and 40 are pivotally connected to the top face of the protractor or base member 8 by means of rivets 43 and 44. The L-square 28 is thus shiftable relative to the straight edge 10 of the protractor with the scale arm 36 in parallel relation in known manner of operation of a drafting machine.

In order to enable the user to hold the protractor 8 in non-shifting relation at a selected place on the drawing with one hand and also permit the same hand to manipulate the L-square 28 throughout an area of the drawing sheet adjacent the protractor I have provided on the bottom face of the protractor or base 8 sufficient antiskid surface 45 to enable said base to be held in position on the drawing while the weight of the user's left-hand rests the top of the said base. For this purpose several patches or areas 45 of antiskid surfacing may be used and may be formed of dried rubber cement film or fine grit abrasive suitably fixed on the base.

A slightly cupped hand rest indicated generally at 46 is mounted for rotation on top of base 8 and in parallelism with the latter. The hand rest 46 comprises an upper disc portion 47 which overhangs a considerable area of the base 8 and is dished or cupped at 48 in the upper center thereof so that the heel or outer bottom carpal portion 49 of a user's hand 50 may comfortably and non-shiftably rest thereon while permitting the hand to swivel with its supporting rest relative to the base 8 while the latter is held against sliding or turning on the drawing under the weight of the hand 50 on said hand rest. The disc 47 has an integral hub 51 on the bottom and is rotatably held in slightly spaced relation by a center pin or rivet 52. A simple ball race 53 is interposed between base 8 and disc 47 and it turns freely about the circumference of hub 51. Bearing balls 54 disposed in individual holes in the ball race 53 afford a free turning and steady support for the disc as the hub and disc may turn on the ball bearing support with a minimum of wear on the center pin 52. Disc 70

47 may be of a diameter sufficient to overhang the finger piece 11 by peripherally cutting or notching the disc as at 55. The notch can be brought into registry with the top of the finger piece to render the latter accessible when desired.

It is to be observed that the outer circumference of the race member 53 serves as a limit stop for either the link 39 or the link 40 when said links are turned on their pivots 43 and 44. The links 39 and 40 are thus also prevented from so closely approaching each other in their movements as to impair the parallel positioning.

The holding of the protractor 8 with its straight edge 10 on a given line will be readily understood since either the heel of the hand or one or more fingers of the hand 50 may comfortably rest in the cupped center 48 of the hand rest 46 while the index finger of the same hand may seat in the cupped top 56 of the finger knob 37 on the L-square 28. The index finger may be extended or retracted to shift the L-square relative to the protractor and that part of the hand which rests on member 46 may turn and swing as the hand rest 46 rotates on its bearing support without relaxing the comfortable resting of the weight of the hand on said support and without danger of accidental shifting of the protractor base 8 on the drawing surface. The ability of different users with either large or small hands to quickly adapt themselves to an individually comfortable, rapid and easy mode of operation is to be noted. It will be understood the usual operations of shifting the L-square to successive positions in the field of adjustment of the L-square about the protractor base 8 may be advantageously performed by the same hand which rests on member 46 and thus holds the protractor against shifting on the drawing. When lines are to be drawn the L-square is held firmly by digital pressure on knob 37 while the position of the base 8 is maintained by the weight of the user's hand on member 46.

In order that the digital holding of the L-square 28 and the shifting of said square relative to the protractor may be suited to the greatest ease and comfort for the hand 50 of the user I prefer to provide the drawing scale members 36 and 361 of the L-square and also the link 38 with tapped bores 370 located at suitable distances away from the finger knob 37 and one or more optionally employed finger knobs 3700 are provided for selective mounting in one or more of said bores. In this way the disposition of the finger knob or knobs may be accommodated to facilitate operation by almost any person regardless of the size or of the normal or handicapped condition of the hand to be used for controlling the machine. The selectively employed finger knobs 3700 are desirably lower than the finger knob 37 but all of said knobs have concaved tops to afford easy digital control of the machine and a maximum comfortable support for the entire hand.

A person whose hand is supple and whose fingers are relatively nimble can hold the L-square in an adjusted position and then lightly shift the base 8 to another place for drawing in another area by manipulation with one hand only. The user may conveniently turn the hand rest to bring notch 55 in registry above finger piece 11 and then place digital pressure on the latter and thereafter adjust the protractor about its radial center. Ordinarily the right hand or the pencil in the right hand is employed in as-

sisting in the last mentioned two operations since the act of drawing is momentarily interrupted.

One who draws with the left hand can manipulate the machine as illustrated with his right hand by disposing straight edge 10 on the perpendicular instead of horizontal. Obviously the machines can be made for left-handed persons by pivoting links 39 and 40 on the left-hand side of the protractor 8 instead of on the right-hand side as herein illustrated.

For adapting the instrument to use on a drawing supported by or scribed on a ferrous metal surface I have provided permanent magnets 57 embedded close to the bottom surface of protractor 8 to materially assist in maintaining the position of the latter. The device is thus made available for use in making original layouts on sheet metal and flat surfaces of castings and in checking the same.

The parts other than the jointed parallel arm assembly are desirably made of transparent plastic materials from which they can be inexpensively formed into light weight drafting machines that can be easily carried about in the coat pocket or the briefcase, tool kit or the like.

It should be understood that the primarily portable machine of the invention may be employed in various ways and in various environments with other existing devices. For example the machine may have the protractor or base 8 slidably and guidedly associated with the well known parallel straight edge mechanism commonly found on drafting boards, and if a temporary slidable attachment is desired, the holes 20-20 may receive holding lugs on any suitable friction slide to connect said base with the parallel straight edge device carried by the drafting board.

It is to be observed that by moving the links 39 and 40 about their pivots until arm 39 engages the ball race 53 as a stop, the joint member 39 will assume a position below the straight edge 10 and close to the protractor. The arm assembly can then be jack knifed to a folded position with the L-square superposed over the protractor. When thus folded the device occupies a minimum of space and is storable in the briefcase or the pocket without likelihood of accidental damage.

The machine of the invention will be understood to be subject to modification within the spirit of the invention and the scope of the appended claims.

What is claimed is:

1. In a portable drafting machine the combination with a flexible unit comprising a drafting instrument and a jointed parallel arm assembly having said instrument pivotally connected to one end thereof, of a base pivotally connected to the other end of said arm assembly, an antiskid bottom on said base, a hand rest connected to the top of the base for relative swivel movement in parallelism with the top of said base, and a finger knob mounted on said flexible unit.

2. In a portable drafting machine the combination of a base having an antiskid bottom, a swiveled hand rest connected to the top of the base, a jointed parallel arm assembly pivoted at one end on top of the base, a finger piece extending through the base and adapted for relative rotation and limited axial reciprocation therein, said finger piece having an antiskid

bottom end, a jointed parallel arm assembly pivoted at one end on the top of said base, a drafting instrument pivotally connected to the opposite end of said arm assembly and a finger knob selectively connected to said arm assembly and said instrument.

3. A portable drafting machine comprising a protractor having an antiskid bottom face, a hand rest swiveled at its center on top of said protractor, a parallel arm assembly including a joint member and two pairs of links each having an end pivotally connected thereto in known manner, a drafting instrument having the remaining ends of one pair of links pivotally connected thereto, the remaining ends of the other pair of said links being pivoted to the top of the protractor, and a finger knob on the drafting instrument.

4. In a device of the class described a protractor having an antiskid bottom face, a hand rest swiveled at its center on top of the protractor, a drawing instrument, and a parallel arm assembly connected at its opposite ends on top of said protractor and said instrument respectively.

5. The combination as set forth in claim 4 characterized by the provision of a rotatable finger piece extending through the protractor at the true radial center thereof, said finger piece having an antiskid bottom end adapted to assume a selected position at and slightly below the bottom face of the protractor.

6. The combination as set forth in claim 4 characterized by the provision of a finger piece adapted for rotation and slight reciprocation in the protractor at the true radial center thereof, and by the provision of a notch in the edge of the hand rest adapted for radial alignment with the top of the finger piece and affording digital access to the top of the latter.

7. The combination as set forth in claim 4 characterized by the provision of a finger knob selectively mounted on top of the drawing instrument and arm assembly to permit one part of a user's hand to be supported on the hand rest for swiveled movement therewith relative to the protractor for retaining the latter against shifting on a support surface, while a finger of the same hand controls and selectively shifts the drawing instrument relative to the protractor.

8. The combination as set forth in claim 4 characterized by the provision of permanent magnets embedded in the bottom of the protractor.

9. In a portable drafting machine, a base having an antiskid bottom surface, a swiveled hand rest on top of the base, a jointed parallel arm assembly comprising a first pair of parallel links pivoted at one end at relatively opposite sides of the swivel mounting of the hand rest on top of the base whereby the said mounting serves as a stop limiting pivotal movement of the respective links on the protractor, a second pair of parallel links comprising said arm assembly being pivoted in spaced relation on the drawing instrument, and means on said instrument limiting pivotal movement of said second pair of parallel links.
